UNITED STATES PATENT OFFICE.

THOMAS VAN WAGONER, OF NEWARK, NEW JERSEY.

IMPROVEMENT IN SASH-CORD GUIDES.

Specification forming part of Letters Patent No. **222,967**, dated December 23, 1879; application filed September 11, 1879.

To all whom it may concern:

Be it known that I, THOMAS VAN WAGONER, of Newark, county of Essex, and State of New Jersey, have invented a new and useful Improvement in Sash-Cord Guides, which invention is fully described in the following specification, reference being had to the accompanying drawings, in which—

Figure 1 shows my guide, partly in side view and partly in section. Fig. 2 is an end view thereof.

Similar letters of reference indicate corresponding parts.

This invention relates to certain improvements upon the sash-cord guides for which Letters Patent were granted to me April 16, 1878, numbered 202,492; and the object of the present invention is to furnish a sash-cord guide which is cheaper of construction and possesses much more practical utility than those constructed according to my aforesaid patent.

To this end my invention consists in a cast-metal pulley-casing having embedded in the rear portion of each of its ends, during the process of casting, a flexible sheet-metal strip of sufficient length to be bent around the angle of the inner edge of the mortise in the window-jamb, for securing said pulley-casing in position without the employment of screws or other fastening devices.

Referring to the drawings, the letter A indicates a pulley-casing which is cast in a single piece, with beveled end projections, *b b*, and each end of said casing has embedded in it, during the process of casting the same, a projecting flexible flat sheet-metal strip, C, which is of a sufficient length to be bent around the inner angle or corner of the mortise in the window-jamb, whereby, when the casing is adjusted in position in the mortise, the said sheet-metal strips serve to secure the casing in place without the employment of screws or other fastening devices.

The beveled end projections, *b b*, serve as stops to limit and determine the insertion of the casing in the mortise, and the casing is otherwise formed without the usual flange.

By the described construction of cast-metal casing having the sheet-metal strips C embedded in its rear portion at the upper and lower ends, I am enabled to furnish a sash-cord pulley-guide embodying in its construction the strips for securing it in place at a much less cost and possessing much more practical utility than the sash-cord guides constructed according to my aforesaid Letters Patent.

Cast-metal pulley-casings in a single piece have been heretofore made; but in all such screw-holes have to be drilled in end flanges for securing them in place, which I obviate by my invention; and a sash-cord guide has been made in two parts, in which the face-plate has been separate from the casing and provided with rearwardly-projecting lugs cast in the upper and lower ends of the same, said lugs being turned down to overlap the edges of a casing which carries the pulley, the object being to afford a means of connecting the face-plate and pulley-case, and such constructions are hereby disclaimed.

A sash-cord guide constructed according to my present invention embodies the manifest advantages of a cast-metal pulley-casing in a single piece with the sheet-metal strips for confining it in place, which I consider of great practical utility over the sash-cord guide patented by me, as hereinbefore mentioned.

Having thus described my invention, what I claim is—

A sash-cord pulley-casing cast in a single piece, with end projections, *b*, and having embedded in each of its ends, during the process of casting such casing, a rectangular flexible strip of sheet metal of sufficient length to be bent around the inner angle of the mortise in a window-jamb, substantially as described.

In testimony that I claim the foregoing I have hereunto set my hand and seal this 8th day of September, 1879.

THOMAS VAN WAGONER. [L. S.]
